METHOD OF BRACING THE CIRCUMFERENCE OF GAS-INFLATED RIGID AIRSHIPS

Arthur Förster, Friedrichshafen, Bodensee, Germany, assignor to Luftschiffbau Zeppelin Gesellschaft mit beschränkter Haftung, Friedrichshafen, Bodensee, Germany

Application March 21, 1933, Serial No. 661,918
In Germany April 4, 1932

3 Claims. (Cl. 244—3)

My invention relates to gas-inflated rigid airships and refers to a special method of bracing the circumference of such ships.

Generally rigid airships are built up of cross members, called rings, and of longitudinal girders connecting the circumferences of such rings. It is usual to provide a wire bracing on the outer circumferential plane of the airship which connects the rings and the longitudinals and against 10 which the pressure of the enclosed gas cells bears.

It is advisable to have the wires which serve for such bracing run between corner or crossing points. As generally a plurality of wires extend from one corner point it has become necessary 15 to deflect the wires laterally at the points where they cross the longitudinals by means of special fittings. This method causes additional stresses on the girders in the plane of the tangent.

By my new method these disadvantages are 20 avoided, so that the longitudinals have no such additional stresses. For this purpose I provide special tie wires which extend from corner points intermediate the end corner points to which the main bracing wires are fastened. These tie wires 25 according to my invention are so connected to the main bracing wires that the latter wires are so deflected from the straight connecting line, that they run substantially parallel to each other.

This will be understood best when having reference to the drawing which represents examples 30 embodying my invention.

Fig. 1 is a perspective view on a portion of the outer frame work of a rigid airship composed of longitudinal girders and of cross or ring girders.

35 Figs. 2 to 5, inclusive, represent mere diagrams of the girders with their wire bracing, each figure giving another example.

The circumferential cross or ring girders are indicated at 1 and 2. They are crossed by longitudinal girders 3, 4, 5 and 6. In the example shown in Figs. 1 and 2, there extend two bracing wires 15 and 16 from corner point 7 to corner point 12. Wire 15 is deflected from the straight line between points 7 and 12 by means of tie wire 25 extending from corner point 8; and wire 16 in the same manner is laterally deflected by means of tie wire 26 extending from corner point 13.

50 The bracing system of Fig. 1 is represented in Fig. 2. It will be seen that every bracing wire extends over two squares and that four bracing wires start from each corner point, each corner point having two tie wires for deflecting the main wires.

In the example represented in Fig. 3 we also have four wires from each corner point, and also two tie wires; but the main bracing wires extend over three squares, thus subdividing them into smaller spaces.

5 The bracing system of Fig. 4 comprises six main wires and four tie wires from each corner point, the main wires extending over two squares.

The example represented in Fig. 5 includes also main bracing wires which are not deflected. There are four wires starting from every corner point, two of them run straight to the corresponding other corner point, whereas the two others are deflected by means of tie wires from an intermediate corner point, all main wires extending over 10 four squares.

15 There are other combinations and variations possible in my new bracing system, as will occur to those skilled in the art. Therefore, I do not want to be limited to the details described or 20 shown in the drawing.

What I claim is:

1. A rigid airship hull comprising a plurality of spaced longitudinal members, a plurality of spaced transverse members intersecting said longitudinal members, a plurality of bracing wires extending substantially diagonally between points of intersection of said longitudinal members with said transverse members and crossing without connecting thereto at least one of said longitudinal members, and tie wires leading from the intersections of said crossed longitudinal members with said transverse members and deflecting the bracing wires from straight connecting paths.

2. In combination in a structure having a plurality of spaced transverse structural members with a plurality of spaced longitudinal structural members connecting the transverse members together at spaced intervals, strand means extending from the intersections of the transverse and longitudinal members to the intersection of the next adjacent transverse members and other than the next adjacent longitudinal members without being secured to the next adjacent longitudinal member, and strand means extending from the intersections of the next adjacent longitudinal members and the next adjacent transverse members for holding the first-named strand means in substantially parallel relation throughout the greater part of their length.

3. In combination in a structure having a plurality of spaced transverse structural members with a plurality of spaced longitudinal structural members connecting the transverse members to

gether at spaced intervals, strand means extending from the intersections of the transverse and longitudinal members to the intersection of the next adjacent transverse members and other than the next adjacent longitudinal members and deflecting strand means extending from the intersection of the next adjacent longitudinal mem-

bers and the next adjacent transverse members to the first-named strands, the points of attachment of the deflecting wires with the main strand means being within the outer quarters of each panel width.

ARTHUR FÖRSTER.
